UNITED STATES PATENT OFFICE.

VINCENT G. APPLE, OF DAYTON, OHIO.

CURRENT-REGULATOR.

965,059.

Specification of Letters Patent. Patented July 19, 1910.

Application filed December 21, 1908. Serial No. 468,515.

To all whom it may concern:

Be it known that I, VINCENT G. APPLE, a citizen of the United States, residing at Dayton, in the county of Montgomery and State of Ohio, have invented certain new and useful Improvements in Current-Regulators, of which the following is a specification.

My invention relates to improvements in current regulators for dynamo electric machines, and has for its general object to provide an improved current regulator of simple and highly efficient construction adapted to be made in small sizes for convenient use in gas engine ignition apparatus and the like.

In the drawings in which I have illustrated a practical embodiment of my invention; Figure 1 is a central, vertical longitudinal section of a load regulator diagrammatically illustrating the connection of its electrical parts in a circuit, and; Fig. 2 is a perspective of parts of the variable resistance devices, with some of the elements separated and some broken away to illustrate the construction.

Broadly considered my improved current regulator consists of a variable resistance element of a character highly responsive to variations in pressure, such for example as a pile of carbon plates, arranged for inclusion in an electric circuit and an electromagnetically controlled pressure device, controlling the compression, and therefore the resistance, of the variable resistance element, such controller having its coil arranged for inclusion in an electric circuit.

More specifically, as shown in Fig. 1, I preferably provide an electro-magnet, generally indicated at 10, preferably in the form of an iron-clad structure whereof 11 is the core and 12 the concentric shell, extending far beyond the end of the core, as at 12', to form a housing. For convenient manufacture the core 11 and end disk, or yoke, 13, are made integral and said yoke is inserted in the tubular shell 12, and secured as by pins 14. The coil 15, wound upon the core, has its terminals 16 brought out through an insulated aperture in the plate 13, and the opposite extremity of the core 11 is surrounded by an insulated washer 17 fitting snugly within the shell 12. The armature 18 is a disk, fitting within the housing portion 12' of the magnet shell, for free longitudinal movement therein, and is provided

with a stem 19 extending into a bore 20 made centrally in the core 11, said stem 19 bearing upon a spring 21 backed up by an adjustable screw 22 accessible from the exterior of the magnet. Preferably also the pin 19, which may be of diamagnetic material, extends clear through the armature 18 to provide a projecting point 19' on the side of the armature remote from the magnet core 11.

The variable resistance structure interfitting in and coacting with the shell in the structure illustrated comprises an end plate 23, fitting in an annular recess 12'' in the end 70 of the housing portion 12' of the shell, said end plate being provided with a transverse slot 23' in which are fitted insulating posts or guides 24, one on each side of the axis of the device extending nearly to the armature 75 18. The chamber inclosed by the shell extensions 12' and the end member 23 is insulated by filler segments 25, and a side band 26, and within the insulated space thus provided is arranged the carbon-structure. 80 In general the variable resistance structure consists of two piles of carbon half-disks, or segments, having their outer end members connected with terminal elements fixed in the plate 23, and at their inner ends bridged 85 across by a solid carbon disk, so that through the carbon piles a conductive path may be formed including such piles in series. Specifically I prefer that there be provided upon each side of the insulating guides 24 90 a pile or series of three or more carbon half-disks, there being provided two such piles, as shown at 27, 27', insulated from each other by said guides 24, and a bridging disk 28 establishing a connection between the two 95 piles 27, 27' and receiving in contact therewith the point 19' of the armature 18. I prefer that the surface of the full carbon disk 28 be covered with a sheet of insulation 29, which may conveniently be secured 100 thereto by a coating 30 of shellac, although obviously any other medium may be employed. Preferably also the carbon disk 30 is notched at its sides as at 31, to slide upon the guides 24 and assist in holding 105 them in position by spacing the free ends of said guides.

The bottommost members of the two carbon piles 27, 27' are connected with terminal members extending through and insulated 110 from the end plate 23. To this end I provide a specially constructed end member for

each half-disk pile providing a metallic base 32, from which projects a screw 33 adapted to pass through an insulated aperture 34 in the end member 25, and receive a nut 35 for retaining it in position. The lowermost carbon half-disk has its under surface copper-plated as at 36, and the copper-plated surface is attached to the metallic base 32 and the terminal screw 33 by a body of solder, as indicated at 37. Now it will be seen that in its assembled condition the regulator consists of a completely closed metallic case, without exterior moving parts, presenting exteriorly only the screws 22 and the terminals 16 and 35. In use the terminals 35 are connected in the shunt field circuit *a* of an electric dynamo A, and the terminals 16 are connected at one side of the line *b* across which are connected the translating devices 20 *c* of any suitable character.

In operation, assuming the dynamo A to be driven at varying speeds, as for example, by direct contact with a gas engine of an automobile, the spring 21 may be adjusted 25 by the screw 22 so that at some predetermined speed the device commences its regulating function and prevents any substantial increase in the current out-put. The regulation is accomplished by variation of 30 the resistance in the dynamo field due to variation in the magnetic effort of the electro-magnet. When the predetermined maximum output of say 5 amperes is reached the magnet begins to draw the armature away 35 from the carbon pile, weakening the pressure thereon and tending to increase the resistance in the field circuit, and the tendency of the dynamo to increase its output, due to an increase in speed, is counterbalanced by 40 the tendency of the electro-magnet to weaken the pressure upon the carbon pile and thereby to increase the resistance in the field circuit and cut down the strength of the field, so that in practice a maximum out-

put may be imposed upon the dynamo which 45 will be substantially retained through a wide variation in speed above some normal predetermined rate.

While I have herein described in some detail a specific embodiment of my invention 50 which I believe to be new in many of its details of construction, it will be apparent to those skilled in the art that the structural details might be widely varied without departure from the spirit and scope of my invention, and I do not desire to be understood as limiting my invention to the specific construction illustratively indicated for purposes of disclosure, further than as specified in the claim. 55

Having described my invention, what I claim is;

In a device of the character described, the combination of an electro-magnet, comprising a core, a winding on said core, a shell 65 surrounding said winding and extending beyond the core, said core being centrally bored, an armature within the shell and provided with a pin projecting into the bore of said core, a spring within the bore exerting a tension on the armature pin, means for adjusting said tension, a cap covering the free end of the shell, insulating guides extending inward from said cap, carbon plates on opposite sides of said guides and 70 separated thereby, a bridging conductive member connecting the innermost carbon plates, and receiving the thrust of the spring-pressed armature, and separated electrical conductors connected with the outermost plates of the carbon piles, and extending to the exterior of the structure. 75

In testimony whereof I hereunto set my hand in the presence of two witnesses.

VINCENT G. APPLE.
